Filed Aug. 26, 1968, Ser. No. 13,267

Term of patent 7 years

Int. Cl. D26—02

U.S. Cl. D48—20

FIG. 1

FIG. 1 is a side elevational view of the lamp showing my design.

FIG. 2 is a top plan view thereof.

In FIG. 1 the five immediately facing panels on the skirt of the lamp constitute a repeat unit, being one of three repeat units surrounding the circular skirt.

The opposite side of the lamp is substantially the same in appearance as the side shown in FIG. 1.

I claim:

The ornamental design for a lamp, as shown and described.
